UNITED STATES PATENT OFFICE

137,634

DESIGN FOR AN ELECTROLYTIC WATER PURIFIER

Theodore C. Jones, Louisville, Ky.

Application February 1, 1944, Serial No. 112,397

Term of patent 14 years

(Cl. D16—2)

To all whom it may concern:

Be it known that I, Theodore C. Jones, a citizen of the United States, residing at Louisville, in the county of Jefferson and State of Kentucky, have invented a new, original, and ornamental Design for an Electrolytic Water Purifier, of which the following is a specification, reference being had to the accompanying drawing, forming part thereof.

In the drawing,

Fig. 1 is a perspective view looking toward one

side of an electrolytic water purifier showing my new design, the other side being substantially the same as the side shown; and

Fig. 2 is a side view thereof.

I claim:

The ornamental design for an electrolytic water purifier, as shown and described.

THEODORE C. JONES.
